ARTHUR L. TOWNSEND, OF WASHINGTON, DISTRICT OF COLUMBIA, ASSIGNOR OF ONE-HALF TO ALBERT A. LOHR, OF WASHINGTON, DISTRICT OF COLUMBIA.

RELAY.

1,006,703.

Specification of Letters Patent. Patented Oct. 24, 1911.

Application filed March 23, 1911. Serial No. 616,547.

To all whom it may concern:

Be it known that I, ARTHUR L. TOWNSEND, of Washington, in the District of Columbia, have invented a certain new and useful 5 Relay, of which the following is a specification.

My invention has for its object to provide a self-polarizing relay, which is self adjusting over the whole range of current strength 10 as used in telegraphic work, ready to respond to the slightest changes in the strength of the line current, provided such changes are quick and sharp as when the circuit is opened and closed by the usual telegraph 15 key.

The invention further has for its object to provide a relay whose operative efficiency will not be destroyed by slow changes in the line current, such as occur when there is 20 line leakage due to rain, fog, sleet, snow, etc. In other words, the invention has for its object to provide a relay which will operate efficiently under weak current impulses as well as strong ones, and which will automatically 25 adjust itself and maintain its operative efficiency regardless of the strength of the line current employed.

Generically the invention embodies a relay of the polarized armature type, having provisions 30 for polarizing the armature by the use of a differential magnet, the coils of which are connected in parallel in the line circuit. One of the coils is designed to be slow acting (*i. e.*, slow in "building" up its magnetism and discharging the same) while the other is quick acting, whereby both the make and break movements of the armature will be effected by both an attracting and repelling force operating in unison, under the 35 influence of the field magnet, which may be permanently or electrically excited.

More specifically the invention includes the novel details of construction, combination and arrangement of parts, all of which 40 in their preferred forms, will be first fully described and then be specifically pointed out in the appended claims, reference being had to the accompanying drawing, in which:—

Figure 1 is a perspective view embodying the preferred mechanical arrangement of parts. Fig. 2 is a diagrammatic view of the form shown in Fig. 1. Fig. 3 is a diagrammatic view of a slight modification of the 45 invention. Fig. 4 is a diagrammatic view of

a further modification. Fig. 5 is a diagrammatic view of still another modification, in which the field magnet is permanently excited.

In the drawing in which like numerals 60 and letters of reference indicate like parts in all of the figures, 1 is the base upon which the cores 2 of the field magnet are supported from the standard 4.

3 designates the pole pieces of the field 65 magnet which may be adjustably connected to the cores 2 if desired.

5 is the core of the differential magnet which is secured to the standard 4 and carries the windings 11 and 12 of the differential 70 magnet. In order that the winding 12 may be rendered slow acting, a non-magnetic sleeve 6 is mounted around the core 5 beneath the winding 12 so as to promote eddy currents and prevent the core section of the 75 magnet 12 building up or losing its magnetism as rapidly as does the core 5 under the winding 11.

7 designates the coils of the field magnet, and 8 designates the armature which is pivotally suspended at 9 from the core 5 of the differential magnet, the electrical continuity 80 between the armature 8 and the core 5 being maintained through a wire 10.

13 and 14 designate the binding posts to 85 which the line wires L—L (Fig. 2) are joined and to which the coils 7 are connected. The coil 12 of the differential magnet in the preferred form of the invention is connected in series with the coil 7 of the 90 field magnet, so that the line current entering, say via post 13 will in turn traverse the coils 7 and 12 in passing from the binding post 13 to binding post 14. The other coil 11 of the differential which is the quick 95 acting one is connected in series with the line current by having its terminals connected to the binding posts 13 and 14 respectively, a non-inductive resistance 15 being interposed in this connection when the windings 11 and 12 are not relatively designed to allow for the resistance of the winding 7.

When the windings 11 and 12 are properly 100 relatively designed with regard to their respective resistances, the non-inductive resistance 15 may be omitted as will be clear to those skilled in the art.

Instead of winding the resistance 15 non-inductively on the cores 2 as in the preferred 105 form shown in Figs. 1 and 2, the non-induc-

tive resistance 15 may be located as a separate unit as indicated in Fig. 3, and instead of energizing the cores 2 from the line current, they may be energized by passing the current from a local battery 16 through the coils 7 as indicated in Fig. 4, and in that event an inductive resistance unit 17 is connected in circuit with the coil 12 of the differential magnet.

10 Instead of employing an electro-magnet for the field magnet, a permanent magnet may be employed if desired as indicated in Fig. 5.

15 18 and 19 designate the local contacts that 15 coöperate with the armature 8 in closing one or more local circuits, and for convenience in adjustment, the contacts 18 may be pivoted at 20 and secured by suitable clamping nuts 21 as indicated in Fig. 1.

20 22, 23 and 24 are the local circuit binding posts, the contacts 18 and 19 being connected to the posts 22 and 23 respectively, while the armature 8 is electrically connected to the post 24 by the connection 25 (see Fig. 2).

25 In operation, when the telegraph key (not shown) is closed to close the line circuit, the current enters via binding post 13 and dividing, passes through coils 7-12 and 15-11 (in a divided circuit), to the binding post 14, thus energizing the pole pieces, say S and N as indicated in Fig. 2. The coils 11 and 12 of the differential magnet are so wound as to neutralize one another when fully "built up"; that is to say, when the 35 magnetic "peak" has arrived in the core 5 under both coils. Thus the coils 11 and 12 demagnetize the armature 8 at a particular time. When the circuit is first closed, however, the coil 11 being quick acting, builds 40 up its magnetism in advance of the slow acting coil 12, thus energizing the armature 8, say with a N polarity at the same time the coil 7 energizes the pole pieces 3 with an S and N polarity. Therefore upon the closing 45 of the line circuit the armature 8 will be attracted by one of the pole pieces 3 (S) and simultaneously repelled by the other (N), thereby causing the armature 8 to close the local circuit at contact 18. By this time the 50 magnetism due to coil 12 will be fully built up and the effect of coil 11 neutralized, thereby demagnetizing the armature 8 which will however, remain in contact with the contact 18 until the line circuit is broken to permit the field magnet to become deenergized.

55 Upon breaking of the line circuit an inductive current will be set up in the coils 7 in the same direction as the energizing current, thereby maintaining a current flow through 60 the magnet 12 in the said direction and a reverse current in the magnet 11, thus causing a reversal of the polarity of the differential magnet, (and consequently a reversal of the polarity of the armature 8) and cause the S 65 pole piece 3 to repel the armature 8 (which

now has a S polarity) and causing the N pole piece 3 to attract the armature 8 to break the local circuit at 18. As soon as the local circuit at 18 has been broken the counter-electromotive force will have died down 7 and the differential magnet and armature become deenergized and also the field magnet will be deenergized and the armature 8 will hang neutral.

It should be understood that the magnetism in the field magnets 3 does not die down as rapidly as that in the differential magnet, owing to the large inductive capacity of the field magnet so that the armature polarity will be given time to change on the break 8 of the circuit in the line.

From the foregoing, it will be observed that there are a great many different ways in which the instrument can be constructed without departing from the principle of the invention which resides essentially in the provision of the divided circuit, one branch containing inductance and one winding of a differential magnet and the other branch containing the other winding of the differential magnet, whereby the polarity of the armature may be reversed on the break of the line circuit.

When the instrument is constructed so that the field magnets are excited by a local battery (Fig. 4) or by a permanent field (Fig. 5) the instrument can then only be used in circuits of constant direction of current, as a reversal of the direction of current would cause a reversal of the Morse signals coming from the local contacts of the relay. These forms however, will be well adapted for pole changers and transmitters on multiplex apparatus, where the direction of the local current is always the same and where it is necessary for the armature to be held firmly against either contact when not operating.

The forms shown in Figs. 1, 2 and 3 are adapted for use regardless of the direction of the line current.

From the foregoing description taken in connection with the accompanying drawing, it is thought the complete construction, operation and advantages of the invention will be clearly apparent to those skilled in the art.

What I claim is:-

1. In a relay, a differential armature polarizing magnet, including a slow acting coil and a quick acting coil connected in the line circuit.

2. In a relay, a field magnet having relatively fixed poles, an armature movable between said poles and means for reversing the polarity of said armature on the "break" of the line circuit.

3. In a relay, a field magnet having relatively fixed poles, an armature movable between said poles, said field magnet including energizing coils in the line circuit, combined

with a differential armature polarizing magnet whose coils are also connected in the line circuit.

4. In a relay, a field magnet, an armature movable between the pole pieces thereof, combined with a differential armature polarizing magnet whose coils are connected in the line circuit, and means causing one of said differential magnet coils to "lag" in action behind the other.

5. In a relay, a differential armature polarizing magnet including a slow acting coil and a quick acting coil connected in parallel in the line circuit.

15 6. In a relay, a field magnet, an armature movable between the pole piece thereof, energizing coils for the field magnet connected in the line circuit, combined with a differential polarizing magnet, one coil of which is in series with the field magnet coils.

25 7. In a relay, a field magnet, an armature movable between the pole piece thereof, energizing coils for the field magnet connected in the line circuit, combined with a differential polarizing magnet, one coil of which is in series with the field magnet coils, and a non-inductive resistance in series with the other coil of said differential magnet.

8. A polarized relay including an armature movable between relatively fixed pole pieces, a differential polarizing magnet, the coils of which are connected in parallel in the line circuit.

35 9. In a relay, a divided circuit, an inductance and one winding of a differential magnet connected in one branch of said circuit, the other branch of said circuit including the other winding of said differential magnet.

40 10. A polarized relay including an arma-

ture movable between relatively fixed poles, combined with a differential polarizing magnet including a quick and a slow acting coil connected in parallel in line circuit.

11. A polarized relay including an armature movable between relatively fixed poles, combined with a differential polarizing magnet including a quick and a slow acting coil connected in parallel in line circuit, and an inductive resistance in circuit with one of said coils.

12. A polarized relay including an armature movable between relatively fixed poles, combined with a differential polarizing magnet including a quick and a slow acting coil connected in parallel in the line circuit, an inductive resistance in circuit with one of said coils, and a non-inductive resistance in circuit with the other of said coils.

13. In a relay, a divided circuit, one branch of which contains an inductance and one winding of a differential polarized magnet, and the other branch of which contains the other winding of said magnet, and means for retarding the action of one of said windings.

14. In a relay, a divided circuit, one branch of which contains an inductance and one winding of a differential polarized magnet, and the other branch of which contains the other winding of said magnet, and means for retarding the action of one of said windings, said retarding means comprising an eddy current producer over the core of said last named winding.
